SLIDE FASTENER

George Henry Clifford Corner, Birmingham, England, assignor to Hookless Fastener Company, a corporation of Pennsylvania

Application April 4, 1933, Serial No. 664,386
In Great Britain May 3, 1932

14 Claims. (Cl. 24—205)

This invention relates to slide fasteners of the type described in the patent to Sundback 1,219,881 in which a pair of flexible stringers, including interlocking elements, are moved into or out of an interlocked relation by means of a slider which may travel along the stringers.

Various arrangements have been used for locking the slider at any desired point along the stringers in order to prevent unintentional opening of the fastener, either when partially or fully closed, for example as shown in the patent to Whitney 1,598,183. Such devices are limited in their application because the means for operating the lock and the slider was accessible from one side of the slider only.

One of the objects of the present invention is to provide a lock slider which can be readily operated from either side of the fastener to which it is applied. More specifically it is an object to provide a slider with a pull on either side for moving the slider to open and close the fastener, it being so arranged that either pull will automatically unlock the slider when it is desired to move it and the lock will automatically hold the slider when the pull is released.

Other objects and advantages will be apparent from the accompanying description and drawing in which:

Fig. 1 is a plan view of a slide fastener embodying one form of my invention.

Fig. 2 is a longitudinal section of the fastener on the line 2—2 of Fig. 1.

Fig. 3 is a longitudinal section of the slider showing a modified form of locking means.

Fig. 4 is a cross section of the slider on the line 4—4 of Fig. 3.

The fastener has interlocking elements 10 clamped to the corded edges 12 of fabric tapes 14 forming stringers which may be interlocked or disengaged by a slider 15 having upper and lower channel-shaped wings or plates 16 and 18 joined by a neck 20 and provided with a sliding pull or handle 22. As thus far described the construction is well known.

Referring to Fig. 2, a lock in the form of a bar 24 is pivoted to a fulcrum or lug 25 on the upper plate 16 and carries a locking pin 26 projecting through the plate. The bar is normally urged by a spring 30 to press the pin 26 into the spaces between the interlocking elements 10 on one of

the stringers. Preferably the side of the pin facing the throat or right hand end of the slider, as seen in Fig. 2, is rounded so that it can automatically ride over the interlocking elements against the force of the spring when the slider is being moved in a direction to close the fastener, and the opposite face of the pin is square to engage an interlocking element and prevent opening of the fastener. The bar is T-shaped in cross section to facilitate the attachment of the pull 22 by means of the prongs 31. The top of the T is turned down at the ends of the bar, as shown at 32 and 34, to provide a finished appearance as well as a retaining pocket for the spring 30 and a retaining end or stop for the pull 22. The shape of the end 34 provides a cam face engaged by the prongs 31 to automatically release the locking pin 26 whenever the pull is positioned parallel to the slider body and actuated in a direction to open the fastener. The end 34 is turned out to provide a stop lug 36 which in cooperation with a cap 38 limits the outward movement of the pin 26.

A link 40 secured to the bar 24 passes through the throat of the slider between the disengaged portions of the stringers, terminating in a triangular eye 42 carrying a pull chain 44. The link is normally held by the force of the spring 30 so that the triangular eye is within a conical hole 45 in the lower plate 18, as shown in Fig. 2, but a pull on the chain in any direction tending to open the fastener causes the eye to ride on the cam face formed by the conical walls and thus pull the link to release locking pin 26.

In the modified form shown in Figs. 3 and 4, the wings 46 and 48 are provided with hooks 50 and 52 to which are secured a U-shaped spring member 54 held in the longitudinal center of the slider by lugs 56. The spring is T-shaped in cross section and the pull 22 is slidably secured thereon by the lugs 31. One end of the spring carries the locking pin 57. Fulcrums 60 and 62 are formed between the lugs 56 on which the spring member can rock.

The pull may travel on one side of the slider between the dotted line position *a* and the dotted line position *b* shown in Fig. 3. The fastener is opened by exerting force on the pull in the proper direction, the pull being held at any convenient angle, usually at the locking pin end of the spring, which latter is formed with the cam surface which 50

insures release of the locking pin 57 even when the pull is operated parallel to the slider as indicated by the dotted lines *a*. The lug or hook 52 acts as a stop to prevent excessive movement of the spring.

The pull member passed across the neck of the slider can be operated on the other side between the positions *c* and *d* indicated in Fig. 3. When the pull is in position *c* it abuts against a stop 64. 10 When in this position and pulled in a direction tending to open the fastener, it exerts an outward force on the U-shaped spring 54 causing it to rock about the fulcrum 62 on the opposite side of the slider and thus release the locking pin. 15 The inherent elasticity of the spring member 54 automatically presses the pin 57 into locking position whenever the pull is released from any position.

A slide fastener fitted with a slider according 20 to the invention is convenient to open or close from either side of the article to which it is attached and as the locking mechanism is operable from either side there is no difficulty in releasing same when it is desired to open or close the fastener.

While I have shown and described in this application embodiments which my invention may assume in practice, it will be understood that these embodiments are merely for the purpose of 30 illustration and description and that various other forms may be devised within the scope of my invention as defined in the appended claims.

What I claim as my invention is:—

1. For slide fasteners of the type having a pair 35 of flexible stringers provided with interlocking elements, a slider adapted to move along the stringers to interlock or disengage the elements, means carried by the slider for locking the slider at any desired point along the stringers, a control for the locking means on one side of the slider and a second and separate control for the locking means on the other side of the slider.

2. For slide fasteners of the type having a pair 45 of flexible stringers provided with interlocking elements, a slider adapted to move along the stringers to interlock or disengage the elements, a locking member on the slider, spring means carried by the slider tending normally to hold the locking member in position to lock the slider 50 and means on each side of the slider for moving it along the stringers, said last mentioned means being constructed and arranged automatically to release the locking means upon being operated in a direction tending to disengage the elements.

3. For slide fasteners of the type having a pair 55 of flexible stringers provided with interlocking elements, a slider adapted to move along the stringers to interlock or disengage the elements, a lock carried by the slider for securing the slider 60 at any desired position along the stringers, means including a bar tending normally to hold the lock in locking position, a fulcrum for said bar on one side of the slider, and means operable from the other side of the slider for rotating the bar 65 on the fulcrum to release the lock.

4. For slide fasteners of the type having flexible stringers provided with interlocking elements, a slider mounted on said stringers and movable along the same to engage and disengage the elements, a locking member on one side of the slider and movable relative thereto into and out of locking engagement with the fastener elements, and a lock operating member permanently 70 located on the other side of the slider and con-

nected to said locking member for moving the same relatively to said slider.

5. For slide fasteners of the type having a pair 5 of flexible stringers provided with interlocking elements, a slider adapted to move along the stringers to interlock or disengage the elements, a lock on one side of the slider, resilient means normally tending to move the lock to locking position and means operable from the other side of the slider moving the lock to unlocked position.

6. For slide fasteners of the type having a pair 15 of flexible stringers provided with interlocking elements, a slider adapted to move along the stringers to interlock or disengage the elements, a bar pivoted on one side of the slider, a lock carried by the bar, resilient means acting on the bar to move the lock to locking position and means operable from the other side of the slider for overcoming the resilient means.

7. For slide fasteners of the type having a pair 20 of flexible stringers provided with interlocking elements, a slider adapted to move along the stringers to interlock or disengage the elements, a bar pivoted on one side of the slider, a lock 25 carried by the bar, resilient means acting on the bar to move the lock to locking position, means operable from the other side of the slider for overcoming the resilient means and a pull on the bar for opening and closing the slider, the bar 30 being constructed and arranged automatically to move the lock to unlocking position when the pull is operated in a direction to disengage the interlocking elements.

8. For slide fasteners of the type having a pair 35 of flexible stringers provided with interlocking elements, a slider adapted to move along the stringers to interlock or disengage the elements, a bar pivoted to one side of the slider, a lock 40 carried by the bar, and means secured to the bar and passing through the slider for operating the bar from the opposite side of the slider to move the lock.

9. For slide fasteners of the type having a pair 45 of flexible stringers provided with interlocking elements, a slider adapted to move along the stringers to interlock or disengage the elements, a U-shaped member extending on both sides of and movably mounted on the slider, a lock controlled by movement of said member, and a pull 50 attached to said member for moving the slider, said member being constructed and arranged to be moved by said pull from either side of the slider to control the lock.

10. Apparatus defined in claim 9 in which the 55 U-shaped member is resilient and normally tends to hold the lock in locking position.

11. For slide fasteners of the type having a pair 60 of flexible stringers provided with interlocking elements, a slider adapted to move along the stringers to interlock or disengage the elements, a bar pivoted on one side of the slider, a lock 65 controlled by the bar, said bar having an extension passing through and disposed on the other side of the slider, and a pull operable on the extension for controlling the lock.

12. For slide fasteners of the type having a pair 70 of flexible stringers provided with interlocking elements, a slider adapted to move along the stringers to interlock or disengage the elements, means on one side of the slider for locking it at any desired point along the stringers and means passing through the slider for operating the lock from the opposite side of the slider.

13. For slide fasteners of the type having a 75

5 pair of flexible stringers provided with interlocking elements, a slider adapted to move along the stringers to interlock or disengage the elements, a bar mounted on one side of the slider, a lock carried by the bar, a pull member slideable on the bar and means secured to the bar and passing through the slider for operating the lock from the opposite side of the slider.

14. For slide fasteners of the type having a

pair of flexible stringers provided with interlocking elements, a slider movable along the stringers for interlocking or disengaging the elements, a locking member secured to one side of the slider, a pull secured to the locking member and means passing through the slider for operating the locking member from the opposite side of the slider.

GEORGE HENRY CLIFFORD CORNER.
